CLAIM

The ornamental design for a vehicle stand, as shown and described.

DESCRIPTION

FIG. 1 is a top view of a vehicle stand illustrating my new design, wherein a front of the stand is elevated;

FIG. 2 is a back view thereof;

FIG. 3 is a left side perspective view of the vehicle stand with an unelevated front;

FIG. 4 is a right side perspective view of the vehicle stand with an unelevated front;

FIG. 5 is a top view of the vehicle stand rotated 90 degrees with an unelevated front;

FIG. 6 is bottom view of the vehicle stand with the front of the stand in a declined position;

FIG. 7 is a right view of the vehicle stand with an unelevated front;

FIG. 8 is a left view thereof;

FIG. 9 is a front view thereof;

FIG. 10 is a back view thereof;

FIG. 11 is a top view thereof; and,

FIG. 12 is a bottom view thereof.
